UNITED STATES PATENT OFFICE.

WALTER MINOR BRADLEY, OF NEW HAVEN, CONNECTICUT.

BLOWPIPE.

No. 810,257.

Specification of Letters Patent.

Patented Jan. 16, 1906.

Application filed May 22, 1905. Serial No. 261,589.

To all whom it may concern:

Be it known that I, WALTER MINOR BRADLEY, a citizen of the United States, and a resident of New Haven, in the county of New Haven and State of Connecticut, have invented a new and Improved Blowpipe, of which the following is a full, clear, and exact description.

My invention relates to blowpipes, and especially to those adapted for mineralogical work and the like, in which it is desired to secure either an oxidizing or a reducing flame of a constant character. Its principal objects are to provide means for adjustably supporting the blast-nozzle with relation to the flame and for effectively supplying air-pressure thereto.

Reference is to be had to the accompanying drawings, which form a part of this specification, in which similar reference characters designate similar parts in all the views.

Figure 1 shows one embodiment of my invention in side elevation. Fig. 2 is an enlarged side elevation, parts being broken away, of a portion of the carrier and blast-tube supported thereon with parts in section. Fig. 3 is a horizontal section on the line 3 3 of Fig. 2, and Fig. 4 is a section on the line 4 4 of Fig. 1.

10 designates a standard which in the present instance consists of the combustion-tube of a Bunsen burner, this tube being supported upon the ordinary base 11 and having connected to it a supply-tube 12, through which gas may be delivered. Surrounding the burner-tube is the usual perforated controlling-sleeve 13, and supported within said tube is an inner tube 14 for varying the character of the flame.

Engaging the standard is a carrier A for a portion of the blowpipe. This carrier comprises a clamp furnished by a pair of pivoted members 16 16, which are curved at 17 to encircle the standard. One of these members is extended at 18 to surround and retain an arm 19, which is conveniently of angular form, having a vertical portion extending substantially parallel to the standard, and an outwardly-extending portion 20, which, as illustrated, lies at an angle to the other member of the arm of somewhat more than ninety degrees. Movable upon the portion 20 of the arm is a clamp having pivoted members 21 21, which have angular ends 22, embracing the arm. Both this clamp and

that operating upon the standard have springs 22^a, surrounding their pivots to normally maintain the engagement of the members. One of the clamp members has a curved extension 23 beyond its end to surround and hold a blast-tube section 23^a. Upon the end of this tube-section toward the burner-tube is fitted a blast-nozzle 24, having a reduced opening, while at the opposite extremity is a cap 25, the end wall of which furnishes a diaphragm having at its center a very minute or contracted opening 25^a. The cap is adapted to receive or have drawn over it a flexible tube 26, preferably of rubber, which has communicating with its outer end a flexible storage-bulb 27, beyond which and connected with it through a tubular portion 27^a is a flexible pressure-bulb 28, provided at its end opposite the tube 27^a with a valve 29, which resists the escape of air from the bulb when it is compressed.

The vertical adjustment of the carrier upon the standard by means of the lower clamp allows the positioning of the blast-nozzle at any desired height with relation to the flame, while the movement of the upper clamp over the arm places the nozzle closer to or farther from the flame, as may be necessary to secure the proper results. The compression of the bulb 28 fills and expands the storage-bulb, and the air prevented from escaping outwardly by the valve 29 passes through the opening in the cap and is discharged by the blast-nozzle into the flame, the very small area of the diaphragm-opening securing both the necessary tenuity of the air-jet and providing for the retention of the supply within the storage-bulb for a considerable period. It will be seen that the capability for double adjustment of the blast-nozzle permits the securing of exactly the character of flame appropriate to any particular class of work and maintains such flame constant and that the application of pressure to the blast-tube by the bulb system greatly lessens the inconvenience of blowpiping as compared with the customary method of supplying air from the lungs. If it is not desired to put the attachment into active use, the carrier may be lowered on the standard, thus removing it from the vicinity of the flame, and even in its raised position it in no wise interferes with the removal or insertion of the inner tube of the burner.

Having thus described my invention, I

claim as new and desire to secure by Letters Patent—

1. A blowpipe attachment comprising a pair of pivoted jaws, an arm fixed to one of said jaws, a second pair of pivoted jaws engaging the arm, and a tube carried by one of these last-named jaws.

2. The combination with a burner-tube, of a pair of pivoted jaws for engaging the tube, an arm fixed to one of the said jaws, a second pair of pivoted jaws engaging the arm, a tube-section carried between the second pair of jaws, a flexible tube communicating with the tube-section, and a storage-bulb and a pressure-bulb communicating with the flexible tube.

3. The combination with a burner-tube, of a pair of pivoted jaws for engaging the tube, an arm fixed to one of said jaws, a second pair of pivoted jaws engaging the arm, a tube-section carried between the second pair of jaws, and a storage-bulb and a pressure-bulb communicating with the tube-section.

In testimony whereof I have signed my name to this specification in the presence of two subscribing witnesses.

WALTER MINOR BRADLEY.
